UNITED STATES PATENT OFFICE.

WILLIAM BLOORE, OF BURSLEM, ENGLAND.

DESIGN FOR A COVER-DISH.

SPECIFICATION forming part of Design No. 23,251, dated May 8, 1894.

Application filed February 21, 1894. Serial No. 501,049. Term of patent 3½ years. Registered in England December 9, 1893, No. 223,708.

To all whom it may concern:

Be it known that I, WILLIAM BLOORE, a subject of the Queen of Great Britain, residing at Burslem, Staffordshire, England, have invented a certain new Design for a Cover-Dish, (registered in Great Britain December 9, 1893, No. 223,708,) of which the following is a specification.

The leading features of my new design consist in the oval form of the dish having substantially straight ends, and upon its quarters, that is to say upon its sides near the ends, one or more depressions giving a scalloped effect; in the vertical contour of the body of the dish, that is to say, its contour from top to bottom, which begins with a vertical lip or edge, then swelling abruptly outward, and then curving downward and inward in a long sweep to the foot; in the contour of the handles the bases of which rest on said abruptly outward swelling portion of the dish body, and which rise upward and outward in two branches at a steep angle, then curve outward and downward, and are united at their ends by transverse bars; in the cover of corresponding shape to the dish body which rises from the rim, at a slight angle, to the base of an embossment which curves abruptly upward and the top of which is bounded by an arch or curve of slight convexity.

In order to make my design more clearly understood I have illustrated it in the accompanying drawings, in which—

Figure 1 is a side view of a cover-dish embodying the design. Fig. 2 is a plan view of the same. Fig. 3 is an end view.

Referring to the drawings, 1 is the body of the dish having sides 2 which in plan view

appear oval, and straight ends 3. Upon the quarters of the dish, and correspondingly upon the cover are one or more curved depressions 4 giving a scalloped effect. These depressions run downward and inward toward the foot 5, as best seen in Fig. 1.

6 indicates the outwardly projecting or swelling portion of the dish, beginning from the base of a vertical lip 7 and terminating in a long curve which extends to said foot.

8, 9, are the handles of the dish, having bases 10 on the swell 6 from which rise the branches 11, curving upward and outward and united by a bar 12.

13 is the dish cover, which in plan view corresponds at its edge with the contour of the dish body, having oval sides 14, indentations 15 in its quarters and straight ends, 16.

17 indicates depressions in its top surface which extend from the indentations 15 inward to the base of the central embossment 18, and form indentations 19 therein. The embossment is bounded on its top, which carries the handle, by a curve or surface 20 of small convexity, and at or near its sides by more sharply curved surfaces 21.

The dish and cover are at suitable points 65 ornamented by scrolls or figures in low relief as shown.

I claim—

The design for a cover-dish, substantially as described and illustrated.

In witness whereof I have hereunto signed my name in the presence of two witnesses.

WILLIAM BLOORE.
